UNITED STATES PATENT OFFICE

2,235,742

WINDOW SCREEN CATCH

John Forte, Hazleton, Pa.

Application April 20, 1939, Serial No. 269,008

2 Claims. (Cl. 292—202)

This invention relates to a catch or lock and more particularly to a swinging catch for holding a screen in a window casing.

An object of the invention is to provide a pair of catches which will efficiently hold a window screen in a window casing.

A further object of the invention is to provide a catch which will hold a window screen in a window casing and permit the window to be opened and closed.

A still further object of the present invention is the provision of a swinging catch which is simple in operation and cheap to manufacture.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawing—

Figure 1 is an elevational view of the inside of a window screen in a window casing, showing my novel catches holding the screen in place in the window casing.

Figure 2 is an enlarged horizontal sectional view of my novel catch on a screen and the catch being in closed or locked position in a window casing.

Figure 3 is a perspective view of a portion of my novel catch.

Referring in detail to the drawing, 10 is a window screen, comprising wire netting 12 and frame-work 14. The frame-work 14 on the two vertical members has a flange or extension portion 16. The sides of the window casing are indicated by the numeral 18. Catches 20 are secured on the inside of the screen 10 on the opposite vertical members of the frame-work 14.

The catch 20 consists of a handle 22 having a tongue portion 24. A bolt portion 26 comprises an angular extension portion 28. The bolt 26 is bifurcated at 30 and the tongue 24 of the handle 22 is pivotally mounted by a pin 32 to the bifurcated portion 30 of the bolt. The bolt has a pointed inner end 34 which is adapted to be driven into the frame-work 14 of the screen. An escutcheon plate 36 is secured by screws 38 on the vertical members of the frame-work 14 of the screen 10. The catch 20 is adapted to be inserted through an aperture 40 in its accom-

panying plate 36 so that the pointed end 34 is buried in the frame-work 14 of the screen.

As shown in Figure 1, the catches 20 are shown in locked position with the screen 10 held in place in the window casing. The angular portions 28 of the catches 20 when in the position as shown in Figures 1 and 2 abut the inner face of the casing members 18, and with the flange portions 16 of the vertical members of the frame-work 14 of the screen abutting the outer face 10 of the members 18 of the window casing, the screen 10 is held in the window casing. The catches 20 are secured to the inside of the screen, so that the screen can be secured in place from the inside of the window casing. 15

To operate the catches for removing the screen as shown in Figure 1, raise the handles 22 of the swinging catches 20 so that they are perpendicular or at right-angles to the window casing portions 18. Then turn or twist the handle 22 of the catch 20 mounted on the right side of the screen in a counter-clockwise movement, and then twist the handle 22 of the catch 20 mounted on the left side of the screen in a clockwise movement. Now both of the angular extensions 28 of the catches 20 have been moved from behind the window casing members 18, and the screen can then be easily removed. When it is desired that the screen be placed in the window casing, the angular extensions 28 of the catches 20 are set so that they lie behind the frame-work 14 of the screen. Next, the flanges 16 of the vertical members of the frame-work 14 of the screen 10 are made to abut against the outside of the members 18 of the window casing. The handle 22 of the catch 20 mounted on the right side of the screen is twisted in a clockwise movement until the extension 28 of the said catch moves to abut the inside of the casing member 18. Then the handle 22 of the catch 20 mounted on the left side of the screen is twisted in a counter-clockwise movement until its angular extension 28 abuts the inside of the member 18 of the window casing. Now the screen 10 is secured in the window casing. The handles 22 of the catches 20 are pulled down to lie flat against the frame-work 14 of the screen. 40

Various changes in the form, shape and other minor details of construction may be made without departing from the principle or spirit of my invention comprehended within the scope of the appended claims. 50

Having described my invention what I claim as new and desire to secure by Letters Patent is:

1. In combination with a window screen com- 55

- prising a frame, of a lock comprising a bolt member, a lateral extension, and the inner end of the lateral extension having a driving point, the driving point of the lock adapted to be driven into the frame of the screen, a plate member secured to the frame of the window screen and overlying the inner portion of the lateral extension of the lock so as to hold the lock on the frame of the window screen.
- 5 5
10 2. In combination with a window screen comprising a frame, of a lock comprising a bolt

member, a portion extending to one side of the bolt member, a driving point projecting from one side of the said extending portion, the driving point of the lock driven into the frame of the window screen, a plate member secured to the 5 frame of the window screen and overlying the inner portion of the said extending portion of the bolt so as to hold the lock on the frame of the window screen.

JOHN FORTE. 10
